HEAT EXCHANGE DEVICE

Frank J. Fette, Tampa, Fla.

Application August 26, 1936, Serial No. 97,922

7 Claims. (Cl. 257—4)

This invention relates to devices for transferring heat from one fluid to another and has for its special object the provision of units capable of easy assembly for use, or ready removal, and of efficient cleaning. The device is especially adapted for pasteurizing milk without danger of injury through overheating, for pasteurizing beer, for cooling and dispensing beverages, and for cooling liquids at the time of charging them with carbonic acid gas.

Another object of the invention is to provide heat-transfer units in which the surface to be exposed to the liquid to be treated may be formed from smooth, thin plates of stainless steel or other non-corrodible materials.

Other objects of the invention will appear in the description of the preferred embodiments of the invention illustrated in the drawings forming a part of this specification, in which Figure 1 is an elevation, with parts in section and parts broken away, of an assembly for pasteurizing, cooling, and chilling milk; Fig. 2 is a plan view of the device of Fig. 1; Fig. 3 is a plan view of a plate forming one surface of a unit; Fig. 4 is an elevation with parts in section of a device for carbonating beverages; Fig. 5 is a transverse section on an enlarged scale of the elements in a single tank of the structure of Fig. 1; Fig. 6 is a similar transverse section of a modification of the same elements; Fig. 7 is a longitudinal view with portions in elevation and portions in section of a modification in which the assembly of units is completely enclosed; and Fig. 8 is a transverse section in two different planes, on an enlarged scale, of the device of Fig. 7.

It is to be understood that the details of construction, the proportions, and the mode of arrangement of the parts are for the purpose of illustration and not as limiting the scope of the invention.

The device comprises a series of any desired number of similar units separated by intervening gaskets and clamped between rigid end pieces to form a continuous channel for a liquid to be treated, which flows in a thin layer through a flat broad passage between the confronting flat surfaces of thin sheet metal plates, the outer surfaces of the plates forming the wall of a passage on each side of each channel, for a liquid which is maintained at a temperature higher or lower than that of the liquid to be treated.

Each unit consists of two plates 1, each plate having a continuous recess 2 pressed therein substantially parallel with its edges to receive a gasket 3 which may be made of rubber or other

suitable material. Near each end, each plate is provided with one or more perforations or passages 4. In Fig. 3, two circular perforations are shown as spaced apart symmetrically, the metal surrounding each of the perforations being struck up as a frusto-conical projection 5. These projections being equally spaced from the central line of the plates and equally spaced from the end will register with each other when the plates are placed back to back and will serve to fix the distance between the plates. Transversely corrugated or wavy strips of metal 6 are arranged longitudinally and transversely of the plates 1 between the ribs 7 formed by pressing the recess 2 into the metal and these strips 6 may be welded or soldered to the plates 1. The meeting rims of the projections 5 will also be welded or soldered together to form a liquid-tight joint around the passages 4. In apparatus in which the liquid is to be under considerable pressure, an additional brace for the central portion of the plates may be provided by securing a wavy strip 8 longitudinally between the two plates of each unit, as indicated in Fig. 5, this strip being omitted in Figs. 1 and 4.

The end pieces 9 are preferably of cast metal such as aluminum, or of one of the light alloys, each member having one surface flat and formed with a recess 10 corresponding in size and position with that of the recess 2 in the plate which will confront it when the units are assembled. Near one end, each end piece has a recess 11 of considerable transverse extent. The opposite surface of each member 9 is formed with strengthening ribs 12 and with a hollow boss 13 to receive an inlet tube 14 or an outlet tube 14', as the member 9 may be used at one end or the other of the series of plate units. In Fig. 5, the boss 13 for the inlet tube 14 is at the top, and it has secured therein a stuffing box fitting 15 externally threaded at 16 to receive a gland 17 having a central cylindrical portion 18 adapted to bear upon packing 19 within a recess in the fitting 15 surrounding the tube 14. The bottom end piece has a short length tube 14' secured within the boss 13 to project an inch or so out of the boss, the amount of projection being sufficient to bring the outer end of the tube 14' about midway of the length of a rubber tube 20 held within a recess in a flanged fitting 21 secured upon the bottom of a tank 22. The exterior of the fitting 21 is threaded to receive a hollow nut 23 which bears upon a gland 24 to compress the tube 20 upon the ends of the metal tubes 14 and 14', as will be explained herein-

after. A bore 25 in each boss 13 connects the recess 11 with the tube 14 or 14' secured within the boss.

The method of assembly of the end pieces with the plate units is simple. With the bottom member 9 resting upon a suitable support, a gasket 3 will be laid in the recess 10, from which it will project more than half of its diameter. A unit of two plates 1 held together in spaced relation by the spacing strips 6 will be placed upon the gasket 3 with the passage or passages 4 at the end of the member 9 remote from the recess 11. The upper surface of this unit will have a recess 2 in which another gasket 3 will be placed, to receive a second unit of two plates which will be set with its passage or passages 4 at the same end as the recess 11 and remote from the passage or passages 4 of the first unit. This procedure will be continued with the passages alternating between the two ends until a sufficient number of units have been used to provide the desired length of channel, whereupon the top end piece 9 will be set upon the gasket of the top unit with its recess 11 remote from the passage 4 of the uppermost unit. When an odd number of units is used, as for example, the three units used in the assembly illustrated in Fig. 5, the inlet and outlet tubes will be at the same end of the assembly as clearly shown in Fig. 1, but when the units are even in number, as shown in Figs. 4 and 7, the inlet tube will be at one end and the outlet tube at the other end.

Liquid entering through the tube 14 at the top in Fig. 5 and passing through the bore 25 will encounter a solid plate 1 opposite the recess 11 and will flow in a thin sheet through the narrow space between the end piece and the top plate until it reaches the passage 4 at the other end. Opposite the passage 4, the solid plate 1 of the next lower unit will cause the liquid to flow through the space between the units until it reaches the next passage 4 at the remote end, and so on to the lowermost unit, where the lower end piece 9 directs the flow to the recess 11 and through the bore 25 to the outlet tube 14'. The space between the confronting surfaces of the plates of two adjacent units is determined by the thickness of the gaskets 3 and such gaskets may of course be made of different thicknesses to provide for the dimensions desired.

The units being identical in construction may be used in any order and freely interchanged. Their symmetrical construction permits either surface to be used uppermost with no change in the results.

The assembly shown in Fig. 5 is used in the apparatus illustrated in side elevation on a smaller scale in Fig. 1. Upon any suitable base, (not shown), two pipes 26 are supported vertically to receive sections 27 of larger pipes, which may be secured to the pipes 26 by setscrews 28. The sections 27 are connected in pairs by transversely arranged angle iron brackets 29 which may be welded to the sections 27 on opposite sides thereof to form flat supporting surfaces for the tanks 22, 30, and 31.

In each tank, an assembly of plate units and end pieces is set with the outlet tube 14' in the fitting 21 and with the central portion of the lower end piece directly above the brackets 29. A clam screw 32 operating in a nut 33 held centrally within oppositely extending arms 34 bears within a recess 35 in the upper surface of the rib 12. The outer ends of the arms 34 are formed as hooks to engage the pipes 26 beneath the sec-

tions 27, so that when the screw is turned by the handle 36, the sections 27 will resist upward movement of the arms and the screw will act to force the top end piece 9 down upon the units underneath, compressing all of the gaskets 3 and holding the assembly securely in place in the tank. A rubber gasket 37 surrounding the tube 14' beneath the boss 13 serves as a water seal as well as assisting in supporting the boss upon the floor of the tank. Legs 38 at the corners of the lower end member may be used to prevent tilting of the assembly.

While the assemblies are being placed within the tanks, they may be held together by any temporary clamping means and the tubes 14 and 14' will be free to be slid within the stuffing boxes before the glands and nuts are tightened to clamp the packing on the tubes. The space between the tanks will be sufficient to permit the removal and replacement of the plate assemblies without disturbing the position of the tanks or of their supporting brackets.

Each tank is arranged for the circulation of a liquid therethrough entering through the inlet pipes 39, passing through the plate units between the plates 1 through the spaces provided by the corrugated strips 6 and out at the other side of the tank through outlet pipes 40 preferably of larger size than the inlet pipes.

In the case of the center tank, 30, a valve 41 admits water from any system supplying water under pressure, such as an ordinary city water main, and the overflow pipe 42 carries the water away from the tank to a sewer or other place of discharge. The water will ordinarily be somewhat cooler than the atmospheric temperature.

Since the arrangement shown in Fig. 1 is primarily meant for use in pasteurization of milk, the tank 22 is supplied with water heated to a temperature slightly above 142° by an electric heater unit 43 mounted within a small tank 44 and controlled by a thermostat 45 having its plug secured within the T 46 in the outflow side of the circuit, and a pump 47 acting to force the heated water through the pipe 48 to the inlet pipes 39 of the tank.

The lowermost tank, 31, is arranged to be supplied with a brine maintained at a temperature just above freezing in a refrigerator (not shown) from which the pipe 49 leads to the pump 50 which forces the brine through pipe 51 to the inlet pipes 39 of the tank 31, the overflow pipe 52 returning the brine to the refrigerating means for further cooling. Both circulating pumps may be driven by a common motor 53.

Milk entering the tube 14, preferably from a suitable strainer, (not shown in Fig. 1 but indicated at 91 in Fig. 7), will flow by the pressure of gravity back and forth through the thin spaces between the exterior surfaces of the units, receiving heat from the heated water flowing through the units, and since this heat is always kept below the boiling point, there is no possibility of the milk being cooked at any point during its flow through the pasteurizing assembly. The rate of flow will be regulated to make the time of treatment as long as may be necessary. The number of units may be increased at will for greater capacity of the assembly without other changes in the system.

From the pasteurizing tank, the milk will flow down into the assembly in the cooling tank 30 to be reduced in temperature from 142° to that of the water system, and from the tank 30, the

cooled milk will flow into the assembly in the bottom tank 31, where the brine may be made to chill it to as low a temperature as is desirable. While the valve 54 which regulates the flow of the milk is shown as discharging into the open top of a milk can 55, it will be evident that it may lead to a bottling device of any suitable kind, so that the milk will not be exposed to the air from the time it is strained until it enters the bottles or the storage can or tank.

It may here be remarked that the ordinary cooler for milk at present in common use, in which milk flows from a strainer over a series of cooling pipes exposed to the air of a dairy, serves to add to the strained milk during the cooling process all of the moisture condensed from the surrounding air, together with bacteria, fungi, and perhaps also insects that may be in the air, whereas the present device serves to exclude all air and protects the milk during the whole process of heating and cooling and chilling.

The modification shown in Fig. 4 is intended for use in carbonating beverages, the apparatus being arranged to introduce the gas into cold liquid under pressure while maintaining a temperature as low as is permitted short of freezing. The assembly illustrated has six plate units, which may be exactly the same in construction as those shown on a large scale in Fig. 5. In view of the fact that the liquids used for carbonating are not subject to rapid deterioration and that daily cleaning of the plates is not necessary, the connections may be made less readily removable than in the apparatus just described for use with milk. The end pieces 9 are shown as clamped upon the intermediate units by two clamp hoops 56, one near each end, and each having a clamp screw 32 with a handle 36. The clamps will be put in place on the assembly before it is inserted into the tank and no further clamping means will be required to hold it in the tank.

A tube 57 screws into the boss 13 and is centrally threaded to receive a lock nut 58 inside the tank 59 and a lock nut 60 outside of the tank, with a rubber gasket or washer forming a water seal between the tube and the tank. Upon the lower end of the tube 57 is screwed a valve fitting 61 having a nozzle 62 regulated by a needle 63. Below the nozzle is an inlet to receive a tube 64 connected with any suitable source of carbon dioxide under pressure, and above the nozzle 62 is an inlet for a cold liquid to be carbonated, supplied by a pipe 65 leading from a suitable container. Neither the container for the liquid nor the carbon dioxide gas tank is illustrated since these form no part of the present invention. The end piece 9 at the top of the assembly has an outlet tube 66 which leads to any suitable bottling device.

The tank 59 may be identical with the tank 31 and will have its refrigerant liquid which flows through the unit assembly maintained at a temperature as low as necessary to obtain the desired degree of carbonation. By arranging the gas to enter the previously cooled and partially carbonated liquid at the point of entry into the apparatus wherein the gas and liquid are forced to flow a considerable distance while constantly being cooled close to the freezing point, the maximum degree of carbonation will be reached for the pressures employed.

In the devices shown in Figs. 1, 4, and 5, the end pieces 9 form one wall of the channel for the liquid both at the intake and at the outlet end. When the end pieces are of cast aluminum

or of certain light metal alloys, the liquid treated or the liquid forced through for cleansing the system may adversely affect the exposed metallic surface, and even when there is no such trouble because of the liquid, the rough exterior left by the casting process will usually require machining to provide a smooth surface suitable for cleaning. The modification shown in Fig. 6 provides a separate sheet metal end plate 67 having a funnel-shaped inlet or outlet portion 68 which extends through the cast end member 69 into a rubber tube 20 held within the boss 13 having a fitting 15, a gland 24, and a hollow nut 23, all of which may be identical in construction and function with the parts similarly numbered in Fig. 5.

In this modification, the liquid does not come into contact with the cast metal of the end piece 69 which serves merely as a backing for the sheet metal plate 67 and as a clamping member for the assembly of pairs of plates 1 connected by passages 4 and wavy strips 6 as in the original form. The gaskets 10 in this modification are shown as moulded in a "diamond" shaped cross section and as having thin lateral flanges or fins extending between the plates and acting as a means for determining the space by which the plate surfaces shall be separated when assembled, and thus regulating the thickness of the flowing film or sheet of liquid.

Instead of providing a separate sheet metal tank to receive the heat-transfer assembly, the end members may be modified to form a closed chamber through which cooling or heating liquid may be forced more rapidly under greater pressure. Such a modification is illustrated in Figs. 7 and 8 in a form intended for pasteurizing milk.

The lower end member may consist of a relatively flat cast plate 72 provided with a plurality of locking bolts 73 pivoted on lugs 74 and having wing nuts 75 for engagement with the tops of spaced lugs 76 formed upon the outer surface of the top end member 77 which is made in the form of a chamber of sufficient size to hold a plurality of sheet metal plate units 78 which may be identical with those previously shown and described in the other embodiments of the invention, but are illustrated in a slightly different form. As in the modification shown in Fig. 6, separate sheet metal plates 79 are used at both the top and bottom to prevent the liquid from coming into contact with the end members 72 or 77, these plates 79 having funnel-shaped inlet or outlet passages 80, 80' extending into rubber tubes 20 held in bosses 13 which have the same fittings and nuts as in the other types.

Ribs 81 extend longitudinally of the end members in the direction of flow to support the end plates 79 and to provide channels 82 between the ribs for the heating or cooling fluid. The gaskets 83 between the plate units are shown as having flat sides with rounded ends provided with fins 84 similar to the fins 71 of the gaskets 10 of Fig. 6. Instead of corrugated strips as in the other forms, the longitudinal members between the plate ribs at the sides where a flow of liquid is not desired may be of an oblong tubular form as shown at 85, while the transverse strips 86 which separate the ends of the plates of each unit may be of zigzag or chevroned form to permit passage of liquid.

The heating or cooling liquid enters the base through a pipe 87 and leaves at the other end at the top of a tube 88 which leads to the discharge pipe 89 secured in the base at the end 75

remote from the pipe 87, neither pipe interfering in any way with the removal or replacement of the top member 77.

The vertical plane of section for the portion to the left of the broken line in Fig. 8 passes through the inlet tube 80, and the plane of section for the portion at the right of the broken line is to the right of the outlet tube in Fig. 7, with the ribs 81, the ends of the units, and the tube 88 all seen in elevation, with the top of the member 77 partly broken away. The scale of Fig. 8 is one and a half times that of Fig. 7.

A gasket 90 in a channel around the periphery of the end member 72 receives the edge of the side walls of the member 77 and the locking bolts 73 draw the member 77 toward the member 72 to cause compression of all the gaskets to hold the entire assembly liquid-tight.

When this form of device is used for pasteurizing milk, a strainer 91 supported above the upper assembly is connected by a tube 92 with the inlet passage 80 at the top of member 77 so that milk may flow back and forth through this pasteurizing assembly and out at the bottom passage 80' in member 72, whence a tube 93 leads it into the top of the cooling assembly beneath. This cooling assembly 94 may be a duplicate of the pasteurizing assembly and may be followed by a still lower chilling assembly as shown in Fig. 1. There will, of course, be automatic devices for heating the water in the pasteurizing assembly and for circulating the chilling brine, but since these are fully suggested in Fig. 1, they have been left out of Figs. 7 and 8.

35 I claim:

1. A heat exchange unit comprising a pair of plates having a peripheral recess on an outer surface providing a corresponding rib on the inner surface, the plates being arranged with the ribs confronting each other separated by members 40 permitting the flow of liquid between the ribs, the plates being connected near one end inward from the recess by a passage for liquid.

2. A heat exchange apparatus in which a plurality of units constructed as in claim 1 are assembled in a series with gaskets within the recesses separating the units to provide a continuous channel through the assembly, and end members clamped upon the assembly of units to hold them in assembled relation, one of said end 50 members being formed to surround the end and sides of the assembly and cooperating with the other end member to form a closed chamber for the passage of a heat exchange liquid.

3. A heat exchange unit comprising a pair of sheet metal plates each having a peripheral rib embossed on one surface and forming a corresponding recess on the other surface and each having at one end inward from the rib a portion struck upward toward the side with the rib and 60 connected with the corresponding struck up portion of the other plate of the pair to form a

passage for a liquid, and means interposed between the ribs and connected therewith to hold the plates together.

4. A heat exchange unit comprising a pair of sheet metal plates each having a rib embossed on one surface near the periphery and forming a recess to receive a gasket on the other surface, wavy metal strips between the ribs and secured thereto at their contact points to hold them together and to provide spaces for liquid, and a liquid-tight connection between the plates forming a passage for a liquid.

5. A device in which a plurality of units constructed as in claim 4 are assembled in a series with gaskets fitted within the recesses to form a continuous liquid passage through the series, and end members clamped upon the ends of the series to hold the units in assembled relation, said end members being provided with inlet and outlet ports for liquid communicating with the liquid passage through the series.

6. A heat exchange apparatus comprising a plurality of sheet metal plates each having a shallow depression adjacent to the periphery of the plate to receive a gasket, gaskets mounted within the depressions and having a thickness greater than twice the depth of the depression whereby to separate the plates to form a thin passage between confronting surfaces of two plates when assembled opposite each other with the gasket in the depressions, and means connecting the two plates between gaskets in pairs, back to back, one of the connecting means for each pair of plates providing a passage for a liquid, and end members clamped upon the units to hold them in assembled relation, said end members being provided with inlet and outlet ports for liquid communicating with the liquid passage formed by the plates and gaskets.

7. In a pasteurizer, a plurality of similar superposed assemblies each comprising a plurality of heat transfer units connected to form a continuous channel for the flow of a liquid to be pasteurized, the uppermost assembly being provided with means for constant supply of heated liquid and with means for automatically maintaining the temperature of the heated liquid within a limited range above the point of pasteurization, and below the boiling point, a lower assembly provided with means for a constant supply of a cooling liquid, and a still lower assembly provided with means for a constant supply of a refrigerant liquid, whereby a liquid to be pasteurized may descend by gravity through a heat transfer means adapted to raise its temperature to the pasteurizing point but below an injurious temperature, thence through a heat transfer means adapted to remove a great part of the heat, and thence through a final assembly adapted to chill the pasteurized liquid to a desired low temperature.

FRANK J. FETTE.
